UNITED STATES PATENT OFFICE.

WILLIAM H. LEWIS, OF HUNTINGTON, NEW YORK, ASSIGNOR OF ONE-HALF
TO GEORGE MURPHY, OF WEST HOBOKEN, NEW JERSEY.

PHOTOGRAPHIC-PRINTING FRAME.

SPECIFICATION forming part of Letters Patent No. 548,782, dated October 29, 1895.

Application filed April 19, 1895. Serial No. 546,313. (No model.)

To all whom it may concern:

Be it known that I, WILLIAM H. LEWIS, a citizen of the United States, and a resident of Huntington, in the county of Suffolk and State of New York, have invented certain new and useful Improvements in Photographic-Printing Frames, of which the following is a specification.

This invention relates to frames for the use of photographers, draftsmen, and others in printing copies of photographs, drawings, and the like. These frames consist, usually, of a rectangular frame, a pressure-board made of two sections hinged together, and spring-clamps which unite the two. There are objectionable features about these prior printing-frames, such as the liability to relative displacement of the negative or drawing and the copy when the operator opens one section of the pressure-board to inspect the copy or copies, for several copies are sometimes made simultaneously, &c.

It is an object of this invention to be able to inspect the copies as often as desired during the printing process without the possibility of the relative displacement of the copies and the original, be it a negative or a drawing.

Another object is the automatic counting of the number of negatives or drawings which have been exposed, and other objects, as will hereinafter more fully appear.

The preferred form of the invention is shown in the accompanying drawings, forming part hereof, wherein—

Figure 1 is a back view of my improved printing-frame. Fig. 2 is a sectional edge view on the plane indicated in Fig. 1 by the line 2 2. Fig. 3 is a view illustrating the operation of the counting mechanism. Fig. 4 is a view illustrating the locking mechanism, and Fig. 5 is a detail of the counting mechanism.

Referring to the form of the invention shown in the drawings, the numeral 3 marks a rectangular frame, of wood or other suitable material, which is provided with shoulders 4 on the inner edge thereof to support the negative or glass, as usual. The frame 3 is provided with the usual recess 5 for facilitating the removal or opening the same to inspect

copies. The pressure-board is made, preferably, of two sections 6 7, which are hinged together by hinges 8, as usual. One of these sections, as 6, is made as narrow as possible in order to allow of the inspection of the copies by opening section 7. The piece at one end of frame 3 is cut down, as at 9, and on this part are preferably placed the counting mechanism and the means for coacting with section 6 to clamp and lock the same to the frame 3. The latter of these consists of the curved and bowed spring cam-arm 10, which is fastened at one end, as by screws 11, to section 6, and the locking and clamping lever 12, which is pivoted by means of the screw or bolt 13 to the end piece of frame 3. This spring-lever 12 is provided with a stud or pin 14, which projects below the same, as indicated in Fig. 2, and coacts with the cam 10 to push the section 6 firmly against the frame 3 and the shoulder 4, the resiliency of the cam 10 and lever 12 permitting of variations in the thickness of the copies and originals. The cam 10 is bowed up (see Fig. 2) to give it room to spring, and stop 15 on section 6 prevents it from bending sidewise. The end piece of frame 3 is recessed at 16 for stud 14. The lever 12 may be recessed, as at 20, and a pin 19 on frame 3 may limit its motion. A metal plate 21 may be placed under the lever 12 for a bearing. The section 7 is provided with the spring-clamp 17 and frame 3 with the ears 18, as usual.

The counter consists of the toothed number-wheel 22, which is pivoted to frame 3 adjacent lever 12. There is a cupped spring-washer 23 under the wheel 22, thus permitting of rocking of the latter on its pivot for a purpose hereinafter set forth. The usual detent 24 prevents back motion of wheel 22. The lever 12 is provided with a pawl or ear 25, beveled on one side, as shown, which coacts with the teeth of wheel 22 to turn the same, as in Fig. 3, and which passes underneath the same, as in Fig. 4, the directions of motion being indicated in each case by an arrow. It will be observed that the described construction is such that the pawl 25 becomes disengaged during the forward motion from the teeth of the number-wheel 22 when it has turned said wheel one tooth. Such construc-

tion permits of greater latitude of motion of lever 12 than would be the case were this not so. It is during the return, as in Fig. 4, that wheel 22 rocks on its pivot by virtue of the 5 spring-washer above described.

Of course the common spring-pawl or spring-pressed pawl may be used, instead of the pawl or toe 25 above described, on the lever 12 to operate the counter.

- 10 The operation of the foregoing is as follows: The pressure-board is removed by opening lever 12 and clamp 17. The negative, &c., are put in place, as usual, after which the board is replaced and lever 12 turned into place. 15 This lever and its toe or stud 14 firmly lock the section 6 to the frame and the lever clamps it in place. This of course means that the negative and prints are firmly held at that end. Clamp 17 is now turned into 20 working position. If it be desired to inspect the prints at any time, clamp 17 is opened and section 7 is turned back and the inspection made. When the negative is to be removed, the clamp 17 and lever 12 are both 25 turned, and it is at this time that the counter is turned one tooth, the detent acting as a pointer. Thus the number of prints made is automatically tallied.

The reference 26 marks a glass plate, (negative,) and 27 marks a copy or print from the same. Reference 28 marks a suitable packing, as a rubber tube, between sections 6 and 7 for excluding light.

A card, as *a*, may be placed under cam 10 30 to receive the number of the negative in the frame.

It will be observed that by the described construction the locking and clamping mechanism locks and clamps one section of the 40 pressure-board or back to the open frame by pressure exerted in two directions at right angles to each other, holding it firmly against the shoulder of the open frame and likewise against one end of such frame.

45 While the foregoing embodies the preferred form of the invention, it is obvious that many changes may be made in details, parts of combinations, and by inversions without departing from the invention.

50 What I claim is—

1. In a printing-frame, the combination of the open shouldered frame, the sectional pressure-board, a cam, and a lever having a toe or stud, one of said cam and said lever 55 parts being on the board and the other on the frame, whereby one section of said board is firmly locked to said frame by pressure acting in two directions, substantially as and for the purpose described.

60 2. In a printing-frame, the combination of

the open shouldered frame, the sectional pressure-board, a cam, and a spring lever having a toe or stud, one of said cam and said lever parts being on the board and the other on the frame, whereby one section of said board is firmly locked to said frame by pressure acting in two directions, substantially as and for the purpose described. 65

3. In a printing-frame, the combination of the open shouldered frame, the sectional pressure-board, a cam on one of said sections, and a lever pivoted on said open frame and having a stud or lip for coaction with said cam, whereby said section is firmly clamped and locked to the frame, substantially as described. 70

4. In a printing-frame, the combination of the open shouldered frame, the sectional pressure-board, a spring-cam on one of said sections, and a spring-lever provided with a toe or stud and coacting with said cam to firmly lock and clamp said section to the frame by pressing the same in two directions, substantially as described. 80

5. In a printing-frame, the combination of the open shouldered frame, the sectional pressure-board, a spring-cam on one of said sections, and a spring-lever pivoted on said open frame and having a stud or lip for coaction with said cam, whereby said section is firmly clamped and locked to the frame, substantially as described. 85

6. In a printing-frame, the combination of the open frame and the pressure-board, with a pivoted clamp, a pivoted counter, and a pawl 90 on said clamp for operating said counter and disengaging therefrom when the counter has been turned one space or interval, substantially as and for the purpose described.

7. In a printing-frame, the combination of the open frame, a pressure-board, the pivoted clamp, a counter mounted on a spring to rock, and a pawl or toe acting on said counter to turn it and to pass it, substantially as and for the purposes described. 100

8. In a printing-frame, the combination of the movable clamp, the counter, a cupped spring-washer under the counter, and a toe on the clamp which turns the counter as the clamp moves one way and which tilts the same 105 as the clamp moves the other way, substantially as described.

Signed at Huntington, in the county of Suffolk and State of New York, this 15th day of April, A. D. 1895.
